WICK-TYPE FUEL BURNER

Filed Feb. 9, 1946

UNITED STATES PATENT OFFICE

2,518,050

WICK-TYPE FUEL BURNER

Averd Nelson, Wisconsin Rapids, Wis., assignor
to Prentiss Wabers Products Co., Wisconsin
Rapids, Wis., a corporation of Wisconsin

Application February 9, 1946, Serial No. 646,516

2 Claims. (Cl. 158—94)

1

The present invention relates to improvements in liquid fuel burners.

More particularly the present invention relates to improvements in burners for the combustion of oil or similar fuel.

The invention is particularly applicable to and will be described in connection with burners of the type employing an annular wick.

An object of the present invention is to provide a burner having improved means for spreading the flame.

A further object is to provide a burner having improved means for distributing air to the fuel delivered by an annular wick.

A further object is to provide a burner including a flame spreader which is simple and sturdy in construction and which performs with improved efficiency.

A further object is to provide a burner well adapted to meet the needs of ordinary service.

Referring to the drawings:

Figure 1 is a view in side elevation of a burner embodying the principles of the present invention;

Figure 2 is a sectional view taken along the plane indicated by the arrows 2—2 of Figure 3;

Figure 3 is a top plan view of the structure illustrated in Figure 1; and

Figure 4 is a bottom plan view of an air distributor and flame spreader unit forming part of the construction illustrated in the preceding figures.

The numeral 10 indicates an annular wick housing having the outer wall or tube 11 and the inner wall or tube 12, said housing being closed at the bottom, as indicated by the numeral 13. The outer wall or tube is illustrated as being extended to a higher level than the inner wall or tube 12. Housed between the walls or tubes 11 and 12 is the annular wick 14 mounted within and secured to the perforated wall 15, which, in a manner well understood in the art, may be manipulated from the exterior of the wall 11 by means of the handle 16. Said handle is mounted at the end of a shaft 17 rotatably supported within the bracket 18 secured to the outer wall or tube 11 of the member 10. Said shaft 17 is provided with a pinion (not illustrated) for engaging in the perforations in the wall 15, whereby turning of the handle 16 will result in the raising or lowering of the wick 14. The perforations in the wall 15 will preferably be spirally disposed, so that said wick in its up and down movements will also have a rotary movement, all of which is well understood by those skilled in the art.

Communicating with the lower portion of the

annular housing 10 is the fuel inlet fitting 19, which may be united to the outer wall 11 of the housing 10. Said fitting 19 is supplied with fuel from the pipe 20, which may be releasably secured to the housing 10 by means of brackets 21 and 22.

The outer wall or tube 11 of the annular housing 10 may be provided with the exteriorly extending bead 23 for strengthening said wall or tube. The inner wall or tube 12 is provided with the interiorly extending bead 24. The bead 24 performs not only strengthening functions, but also acts as an abutment for a bracket 25. Said bracket 25 includes an annular portion 26 fitting within the interior of the inner wall 12 and a flange 27 extending inwardly a short distance beyond the bead 24. The flange 27 is provided with a plurality of fingers 28. In a physical embodiment of the present invention four of said fingers 28 are provided, said fingers being disposed symmetrically with respect to two diameters in right-angular relationship with each other. The bead 24 serves to support an air distributor and flame spreader unit, indicated as a whole by the numeral 29. The fingers 28 serve as hold-down members for the unit 29 in a manner which will be described presently.

The air distributor and flame spreader unit 29 embodies a pair of diametrically disposed plates 30 and 31, which plates are interlocked along the axis of the annular housing 10 by means of a dove-tailed joint. Said plates 30 and 31 have fingers 32 extending therefrom, all in the same direction, circumferentially with respect to the unit 29. Said fingers 32 are adapted to slide underneath the fingers 28 when the unit 29 is inserted within the housing 10 and given a turn in one direction. Release is accomplished by turning the unit 29 in the opposite direction.

Each of the plates 30 and 31 is provided with end portions 33 fitting freely within the inner wall 12 of the wick housing 10. Each of said end portions provides an abutment for supporting an air distributor 34, which forms part of the unit 29. Said air distributor 34 includes a cylindrical wall portion 35 of less diameter than the internal diameter of the wall 12. The upper portion of the wall 34 is bent over at its top portion 36 in the form of an inverted U and is provided with the downwardly extending outer annular portion 37 extending to a level below the top of the wall 12 and providing an annular space between said portion 37 and said wall 12. The cylindrical wall 35 is provided with a plurality of slots 38 adapted to receive fingers 39 extending

from said plates 30 and 31. Said fingers 39, in cooperation with the end portions 33, serve to hold the air distributor 34 in a fixed position axially of the unit 29. However, the air distributor 34 is capable of a slight circumferential adjustment relative to the plates 30 and 31, for purposes which will appear presently.

The wall 35 of the air distributor 34 is provided with a plurality of spaced apertures 40. The outer annular portion 37 is provided with a plurality of spaced apertures 41, said apertures 41 being located at a higher level than the apertures 40. Said apertures 41 are located approximately at the level of the top of the inner annular wall 12 of the housing 10. Preferably the apertures 41 will be smaller than the apertures 40. The wall 35 may be referred to as the inner perforated annular wall and the outer annular portion may be referred to as the outer perforated annular wall of the distributor 34.

The plates 30 and 31 are provided with upstanding portions 42 adapted to support the flame spreader 43. Said upstanding portions 42 are provided with fingers 44 extending through coinciding apertures in the flame spreader 43, being bent over on the top side of the flame spreader 43 to hold said flame spreader firmly upon the upstanding portions 42. The flame spreader is in the form of a canopy and has the central aperture 45. The flame spreader 43 is also provided with the circularly disposed series of holes 46 and a second series of circularly disposed holes 47, preferably arranged in symmetrical relationship with the central aperture 45.

In operation, air entering from the bottom of the burner and passing up within the inner wall 12 will have a plurality of possible courses of travel. Portions of such air adjacent to the wall or tube 12 will pass up through the annular passageway between the wall 35 and the wall or tube 12, part passing up through the annular space outwardly of the portion 37 and part passing through the apertures 41. Air will also pass inwardly of the wall 35, thence through the apertures 40 in the air distributor 34, and such air will be directed through the apertures 41. Still other portions of the air will pass upwardly to the flame spreader 43. A portion of such air will pass through the central aperture 45, and other portions will pass through the two circularly disposed series of holes 46 and 47. Portions of the air will also be directed radially beyond the periphery of the flame spreader 43.

The net effect of the various courses of combustion air will be to provide combustion air directly to the fumes emitted by the wick 14, to spread the flame resulting from combustion of the air and fuel, and to provide combustion air for the core of the stream of combustible mixture.

If by reason of tolerances in manufacture the distribution of air along the various courses should be out of symmetry around the axis of the burner, the air distributor 34 may be given a turn in a circumferential direction due to the slots 38 which receive the fingers 39. By reason of this adjustment the desired symmetry of the flame may be accomplished.

Though a preferred embodiment of the present invention has been described in detail, many modifications will occur to those skilled in the art. It is intended to cover all such modifications that fall within the scope of the appended claims.

What is claimed is:

1. In a burner, in combination, an annular wick housing having an inner tube and an outer tube, said inner tube having its upper edge located below the upper edge of said outer tube, and an air distributor located adjacent to the top of said housing, said air distributor having a tube spaced from the inner annular wall of said housing, said annular wall of said air distributor being provided outwardly thereof with a turned over top portion and a depending edge portion disposed inwardly of said inner annular tube of said wick housing, said distributor wall being provided with a series of circumferentially spaced apertures, said edge portion being provided with a series of circumferentially spaced apertures located in a plane above the plane of said first mentioned apertures, the apertures in said edge portion being located above the inner tube of said housing but below the top of the outer tube of said housing.

2. In a burner, in combination, an annular wick housing having an inner annular wall and an outer annular wall, said inner annular wall having its upper edge located below the upper edge of said outer annular wall, and an air distributor located adjacent to the top of said housing, said air distributor having an annular wall spaced from the inner annular wall of said housing, said annular wall of said air distributor being provided outwardly thereof with a turned over top portion and a depending edge portion disposed inwardly of said inner annular tube of said wick housing, said distributor wall being provided with a series of circumferentially spaced apertures, said edge portion being provided with a series of circumferentially spaced apertures located in a plane above the plane of said first mentioned apertures, the apertures in said edge portion being located above the inner wall of said housing but below the top of the outer wall of said housing.

AVARD NELSON.

Certificate of Correction

Patent No. 2,518,050

August 8, 1950

AVERD NELSON

It is hereby certified that error appears in the printed specification of the above numbered patent requiring correction as follows:

Column 4, line 13, strike out "a tube spaced from the inner annular wall of" and insert instead *an annular wall spaced from the inner tube of*;

and that the said Letters Patent should be read as corrected above, so that the same may conform to the record of the case in the Patent Office.

Signed and sealed this 7th day of November, A. D. 1950.
